UNITED STATES PATENT OFFICE

139,342

DESIGN FOR A WHEELED TOY

Archie N. Perry, Toledo, Ohio, assignor to Dudley W. Moor, Jr., and Eugene M. Belknap, both of Toledo, Ohio

Application June 16, 1944, Serial No. 114,029

Term of patent 14 years

(Cl. D34—15)

To all whom it may concern:

Be it known that I, Archie N. Perry, a citizen of the United States and resident of Toledo, in the county of Lucas and State of Ohio, have invented a new, original, and ornamental Design for a Wheeled Toy, of which the following is a specification, reference being had to the accompanying drawing, forming a part thereof.

In the drawing, Fig. 1 is a perspective view of a wheeled toy showing my new design; Fig. 2 is an opposite side view thereof from that shown in Fig. 1, and Fig. 3 is an end view thereof.

I claim:

The ornamental design for a wheeled toy, substantially as shown.

ARCHIE N. PERRY.
